(57) **CLAIM**

The ornamental design for a notebook radiator, as shown and described.

DESCRIPTION

FIG. 1 is a front, right side, top perspective view of a notebook radiator showing my new design;

FIG. 2 is a rear, left side, bottom side bottom perspective view;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof;

FIG. 8 is a rear elevational view thereof; and,

FIG. 9 is a rear, left side, bottom side bottom perspective view thereof showing the underlying support structure at their deployed positions.

The broken lines depict portions of the notebook radiator that form no part of the claimed design.
